AIRCRAFT CONSTRUCTION

Ivan H. Driggs, Ferguson, Mo., assignor to The
Glenn L. Martin Company, Baltimore, Md.

Application November 4, 1939, Serial No. 302,794

5 Claims. (Cl. 114—66.5)

The present invention relates to flying boats and particularly to the construction of hull bottoms for such boats.

It is usual in a flying boat to provide a step in the hull around the mid point thereof. In operating such a boat, during the take-off, the control of the trimming angle is quite difficult. At the low speeds at which the boat is moving during the take-off, the elevators do not have their normal effectiveness. For that reason the boat ordinarily rides at a trimming angle considerably greater than the angle of least resistance. Of course this high angle of trim causes a considerable increase in resistance, but this increase cannot be avoided because of the necessity for preserving the trim.

The primary object of the present invention is to construct the hull in such a manner that by its movement through the water a substantial force is exerted thereon which acts to aid in keeping the boat trimmed at a lesser angle, nearer to or equal to the angle of least resistance. This of course reduces the trimming angle, and the resistance of the whole craft is reduced. Thus it is possible to accelerate the boat more quickly and to achieve a shorter take-off.

Furthermore, there is a tendency particularly in large boats to tip the boat backward, because of the large forces exerted on the front end thereof. Another object of this invention is to provide means at the rear of the hull which cause a counter moment so as to balance at least in part this tendency. It is a further object to provide means which have a long moment arm or effective leverage, so that the force exerted by the water on a comparatively small area at the rear can balance the force exerted on a larger area at the front.

Furthermore, when a flying boat is moving through the water, the water which is thrown up over the after body creates a drag on the outer surface of the hull. Furthermore, this water is likely to get in the wake of the propeller and to be thrown back on the tail, thus dirtying the tail and possibly obscuring the vision of observers situated therein. Another object of the invention is to provide a hull of such construction that this spraying of the water over the after body is avoided, by laying down the spray and preventing it from rising up into the wake of the propellers.

Still another object of the invention is to provide a construction for accomplishing this last result, in which the lateral spray from the main step in the hull bottom is permitted to escape

freely, so as to avoid any drag on the hull bottom itself when the boat is running on the first step.

These results are accomplished by providing at 5 the rear of the main step a hull portion the rear end of which is provided at its outer edges with a turned over portion sufficient to lay down the spray and prevent it from rising up into contact with the after body and tail portion of the boat. 10 Further objects and advantages of the invention will appear more fully from the following description, particularly when taken in conjunction with the drawing which forms a part thereof.

15 In the drawing:

Fig. 1 shows in side elevation the body of a flying boat embodying my invention;

Fig. 2 is an enlarged view of the lower right-hand portion of the aircraft shown in Fig. 1;

20 Fig. 3 is a contour diagram of the bottom portion of the hull looking from the rear, showing the outline thereof in the different stations 1 to 12 indicated on Fig. 1.

The aircraft includes a fuselage 14 supported by 25 wings 16, and a hull 18. A rearwardly extending portion 20 of the fuselage is adapted to support the usual tail. The present invention involves changes in the construction of the rear end of the hull of such an aircraft.

30 According to the invention, the hull is provided intermediate its length with a usual step 22. Behind this step, the hull bottom has the contours shown in lines 1 to 10 of Fig. 3. At the contour 10 there is a second small step 24, and behind that is a small hull portion 26 which terminates in a point as at 28, the shape of the intermediate part of portion 26 being a simple V as indicated by line 11 in Fig. 3.

The section 23 between the steps 22 and 24 is 35 for the most part of the ordinary V shape, and provided with a keel line 30. At stations 1 to 6, or throughout substantially half its length, the hull portion 23 is preferably of substantially V shape, or, in other words, in any cross section its outline is represented by two straight lines intersecting at the keel line 30. From station 7 to station 10, on the other hand, while the central portion of the hull is of V shape, the outer edges thereof gradually are turned down more and more, reaching the greatest degree of inclination away from the principal planes of the hull bottom at the step 24, or at station 10, thus forming a downwardly turned edge portion 34. At this point, as indicated by the line of dashes marked T—T in Fig. 3, the tangent to the hull

bottom at the outer edge thereof is directed upwardly and inwardly, or, in other words, the hull bottom at this point is turned slightly over beyond the horizontal. The important requirement of the invention is that the portion of the hull at this point be turned downwardly from the normal line of the V bottom, or, in other words, that the tangent to the hull at the edge thereof in any transverse plane should intersect the longitudinal vertical plane of the boat at a point above the point of intersection of the keel line with the same transverse plane.

The portion 26 behind the rear step 24 is preferably of normal V shape, as stated above. From the point 28, the rear line of the body 10 extends substantially directly upwardly as at 32.

The above construction accomplishes the results set forth in the introduction. The spray which is normally sent up at the rear of the hull bottom is by the downwardly curved edge 20 portion 34 turned and flattened down onto the surface of the water, and is thus prevented from spraying upwardly over the rear of the boat. On the other hand, when the boat is riding on the step, spray escaping from the bottom of the forward step 22 is able to escape outwardly and at an angle through the space between stations 1 and 6, without being turned down and without contacting with the rear hull portion, so that a 25 drag on the boat during this stage of its movement is prevented.

At the same time, the turned over portion at the rear of the boat serves to make the force exerted by the water more effective at low speeds, so as to help to regulate the trimming angle and keep it as low as possible, thereby lowering the resistance of the boat. This effect is accomplished because the turned over portion retards the outward flow of the water, and causes the water as it flows outwardly to exert a substantially greater lifting action on the rear end of the boat. As this point is located at a considerable distance behind the center of gravity, the effective force exerted by the water is increased and thus tends to balance the larger force exerted in the front of the boat on a shorter leverage arm about the center of gravity.

While I have described herein one embodiment of my invention I wish it to be understood that I do not intend to limit myself thereby except within the scope of the appended claims.

I claim:

1. In a flying boat, a downwardly convex hull having a step in an intermediate portion thereof 55

and means on the rear part of the portion of the hull behind said step to deflect the spray, the front end of said means being spaced rearwardly from the step by at least about half the length of said portion so as to permit the escape of spray produced by the step.

2. A flying boat comprising a body and a hull bottom, a step in an intermediate portion of the hull bottom, the forward part of the portion of hull bottom behind said step being of substantially V shape, and the rear part thereof being of substantially V shape and having its edges turned downwardly, so that tangents to the edges of such rear part intersect the vertical longitudinal plane of the hull bottom at points above the keel line in the same transverse plane.

3. A flying boat comprising a body and a hull bottom, a step in an intermediate portion of the hull bottom, the forward part of the portion of hull bottom behind said step being of substantially V shape, and the rear part thereof being of substantially V shape and having its edges turned downwardly, so that tangents to the edges of such rear part intersect the vertical longitudinal plane of the hull bottom at points above the keel line in the same transverse plane, a second step at the rear of said portion behind the first step, and a small hull portion of V shape behind said second step.

4. A flying boat comprising a body and a hull bottom, a step in an intermediate portion of the hull bottom, the forward part of the portion of hull bottom behind said step being of substantially V shape, and the rear part thereof being of substantially V shape and having its edges turned downwardly, so that tangents to the edges of such rear part intersect the vertical longitudinal plane of the hull bottom at points above the keel line in the same transverse plane, 30 a second step at the rear of said portion behind the first step, and a small hull portion of V shape behind said second step, said second step being of less vertical dimension than said first step.

5. A flying boat comprising a body and a hull bottom, a step in an intermediate portion of the hull bottom, the forward part of the portion of the hull bottom behind said step being convex, and the rear part thereof being convex and having its edges turned downwardly so that tangents to the edges of such rear part intersect the vertical longitudinal plane of the hull bottom at points above the keel line in the same transverse plane.

IVAN H. DRIGGS.
